US00D820002S

(12) **United States Design Patent** (10) Patent No.: **US D820,002 S**
(45) Date of Patent: **** Jun. 12, 2018**

(54) **CONTAINER**

(71) Applicant: **Johnson & Johnson Consumer Inc.**,
Skillman, NJ (US)

(72) Inventors: **Michael Cannamela**, Atlantic
Highlands, NJ (US); **Evan Rhodes**,
Brooklyn, NY (US); **Max Knecht**,
Brooklyn, NY (US); **Anthony B. Gallo**,
Jr., Warren, NJ (US); **Aimee Sealfon**,
Brooklyn, NY (US); **Ernesto**
Quinteros, South Orange, NJ (US);
Timothy O'Toole, Jersey City, NJ
(US); **Raffaele Mazzei**, Montclair, NJ
(US); **Melissa Dandy**, Hillsborough, NJ
(US)

(73) Assignee: **Johnson & Johnson Consumer Inc.**,
Skillman, NJ (US)

(**) Term: **15 Years**

(21) Appl. No.: **29/564,563**

(22) Filed: **May 13, 2016**

(51) LOC (11) Cl. **23-02**

(52) U.S. Cl.

USPC **D6/542**

(58) **Field of Classification Search**

(57)

CLAIM

The ornamental design for a container, as shown and
described.

DESCRIPTION

FIG. 1 is a top perspective view of the front side of a
container showing our new design.

FIG. 2 is a bottom perspective view of the front side thereof.

FIG. 3 is a front elevation view thereof.

FIG. 4 is a right side elevation view thereof.

FIG. 5 is a rear elevation view thereof.

FIG. 6 is a left side elevation view thereof.

FIG. 7 is a top plan view thereof; and,

FIG. 8 is a bottom plan view thereof.

1 Claim, 6 Drawing Sheets
